J. STAERK

PARING KNIFE

Filed Feb. 29, 1924

Inventor:
JULIUS STAERK

By J. Lee Bain Hinkley
Attest

UNITED STATES PATENT OFFICE.

JULIUS STAERK, OF CHICAGO, ILLINOIS.

PARING KNIFE.

Application filed February 29, 1924. Serial No. 696,042.

To all whom it may concern:

Be it known that I, JULIUS STAERK, a citizen of the United States, residing at Chicago, in the county of Cook and State of Illinois, have invented certain new and useful Improvements in Paring Knives, of which the following is a specification.

This invention relates to improvements in paring knives for chiropodists.

10 One of the objects of the invention is to provide a knife especially adapted for use by chiropodists which may be used to remove callous growths or formations, on the feet, in very thin shavings or chips and 15 which will not disengage or sever any healthy, normal tissue or cuticle.

Another object is to provide such a knife by use of which part of the blade is shrouded so as to be entirely ineffective, 20 leaving the other portions thereof uncovered for useful operation.

A further object is to generally improve devices of this character.

Other objects, advantages and benefits 25 will become apparent from a consideration of the following description when taken in conjunction with the accompanying drawings forming a part hereof, wherein:—

Fig. 1 is a side elevation of the device.

30 Fig. 2 is a rear elevation of the device.

Fig. 3 is a front elevation of the device.

Fig. 4 is a longitudinal central section taken on line 4—4 of Fig. 2.

Fig. 5 is a perspective view of the shield plate.

Fig. 6 is a similar view of a shroud plate interchangeable with the shield plate.

Fig. 7 is a view similar to Fig. 4 showing the shroud plate in place.

40 Fig. 8 is a perspective view of the shroud plate.

Fig. 9 is an end view of Fig. 7.

In all the views the same reference characters are employed to indicate similar 45 parts.

The device is designed more especially for use by chiropodists and is made small for convenience in use; in operation it will remove the protuberances in extremely thin 50 and small pieces and can never penetrate deeply to produce a dangerous or painful wound.

In the drawing a concave cover plate 10 has a threaded stem 11 for insertion into a threaded bore in the end of the handle 12. 55 The cover plate 10 overlies the flexible blade 13 and tensions the blade just as in a safety razor; except in this case the cutting edge is curved while in a safety razor the blade is curved transversely and the cutting edge 60 remains straight. The plate 10 has two depending, spaced lugs 14 which extend downwardly thru the notches 15—15' in the rear of the guard plate 16 and the shroud plate 17. Each of these plates is concavo-convex, 65 the curve of which corresponds with that of the cover plate 10 so that these surfaces are parallel when in place with the flexed blade therebetween.

The plates 15—15' each have a hole 18 70 thru which the stem 11 passes to secure it on the handle.

The guard plate 16 has a slot 19 just in front of the front edge of the blade 13 and a guard bar 20 is tapered to increase the 75 opening thru the slot, and the front surface 22 is slightly rounded to facilitate smooth movement of the tool over the surface operated upon.

The shroud plate 17 has a projection 23 80 which covers or shrouds the mid-portion of the blade 13 and has its corners removed at 24 to permit the corners 25 of the blade to project. These corners may be used for cutting deeply into contracted areas, as when 85 digging out the core of a corn.

Each of the plates 15—15' has a projection 25 which lies between the projections 14—14 to hold the parts in line.

The rear edge of the blade 13 lies against 90 the inner surfaces 14—14 of the cover plate.

The blade 13 is substantially square in plan outline with one edge sharpened.

It will be observed that it is the cutting edge of the blade that is flexed or curved and 95 that the blade is concavo-convex in form across the cutting edge.

Having described my invention what I claim as new and desire to secure by Letters Patent, is:—

1. A tool of the character described, comprising a curved cover plate and a correspondingly curved under plate; a flexible cutting blade between the plates having

a transversely curved cutting edge and means to hold the plates together and to curve the cutting edge of the blade.

2. A tool of the character described, comprising a curved cover plate; a correspondingly curved under plate; a flexible cutting blade between the plates; means to hold the

plates together and to curve the cutting edge of the blade, said under plate covering the mid-portion of said cutting edge, leaving the ends of said edge exposed.

In testimony whereof I hereunto set my hand.

JULIUS STAERK.
